F. J. NELSON.
FASTENER ATTACHMENT FOR RUBBERS.
APPLICATION FILED FEB. 2, 1917. RENEWED FEB. 5, 1919.
1,300,998. Patented Apr. 15, 1919

UNITED STATES PATENT OFFICE.

FRANK JULIUS NELSON, OF HALLOCK, MINNESOTA.

PASTENER ATTACHMENT FOR RUBBERS.

1,300,928.

Specification of Letters Patent. Patented Apr. 15, 1919.

Application filed February 2, 1917, Serial No. 146,188. Renewed February 5, 1918. Serial No. 275,250.

To all whom it may concern:

Be it known that I, FRANK J. NELSON, a citizen of the United States, and a resident of Hallock, in the county of Kittson and State of Minnesota, have invented a new and Improved Fastener Attachment for Rubbers, of which the following is a full, clear, and exact description.

My invention is more particularly intended for application to a pair of rubbers.

The prime object of the invention is to provide a fastening means for rubbers or other articles of foot-wear whereby to fasten the pair together when they are not in use, thereby, in the case of schools and other large gatherings, preventing the loss of time and confusion, as well as inconvenience in locating the rubbers of a pair, and preventing the loss or accidental exchanging of rubbers. The stated object is attained by securing a piece of tape or like flexible strip at its upper end to each article of the pair at the adjacent sides thereof at the interior near the upper edges and providing the free ends of said strips with co-engaging fastening means, whereby the strips, when the rubbers are in use, will lie within the rubbers at a side thereof, the strips being of a length to be brought above the tops of the rubbers for uniting the fasteners, thereby fastening the rubbers of the pair together, thus preventing their separation and at the same time allowing of the pair of rubbers being hung on a clothes hook or the like.

Reference is to be had to the accompanying drawings forming a part of this specification in which similar reference characters indicate corresponding parts in all the views.

Figure 1 is a perspective view of a pair of rubbers having my attachment applied thereto;

Fig. 2 is a longitudinal vertical section of one of the rubbers;

Fig. 3 is a transverse section of a pair of rubbers;

Fig. 4 is a fragmentary plan view showing a modified fastening means;

Fig. 5 is a transverse vertical section of the elements shown in Fig. 4.

The invention is shown applied to the two rubbers A of a pair, though it may be applied to other articles of foot coverings, similarly shaped. In carrying out my invention I apply to each rubber of a pair a

strip 10 of tape or other flexible material and secure each strip at its upper end by a row of stitching 11 or other means, to a side of the rubber, near the upper edge, the respective strips being in practice secured to the corresponding sides of the rubbers and at a point adjacent to the arch.

The strips are of a length to lie at the interior of the rubbers against the sides thereof as shown in Figs. 2 and 3, when the rubbers are not fastened as when ready for use. At the free ends of the respective strips 10, co-engaging fastening means are provided which in the form shown in Figs. 1 to 3, consists of a button 12 on one strip and a button-hole 13 in the other. The strips are of a length so that they may be brought upward as shown in Fig. 1 and indicated in dotted lines Fig. 3, to extend above the tops of the rubbers and permit the fastening means to be engaged, whereby the united strips will constitute a tie or connection between the two rubbers of the pair, securely fastening the same detachably together. Thus, the rubbers will be prevented from being accidentally separated or exchanged.

In the form shown in Figs. 4 and 5, the respective strips 10^a are provided with a known form of fastening means comprising a hook 12^a and an eye 13^a instead of the button and button-hole in the first described construction.

Having thus described my invention I claim as new, and desire to secure by Letters Patent:

1. A pair of foot coverings having a flexible strip permanently secured to each article of the pair at a corresponding point at the interior thereof, at a side of each, near the upper edge of said side, and at the upper end of the strip, the said strips being of a length to lie in a depending position at the interior of the articles when the strips are unconnected, the free ends of the strips having co-engaging fastening means and being flexible to dispose the free ends above the tops of the articles for engagement of the fastening means.

2. A pair of foot coverings having fastener strips permanently secured at one end thereof to each article of the pair, said fastener strips being provided with co-engaging fastening means, the strips when unconnected being foldable at the interior of the respective article and being of a length to

permit of their free ends being brought above the articles and fastened to constitute said strips a connecting medium between the articles.

5 3. A pair of foot coverings having means to fasten the pair together, said means consisting of flexible strips secured to the re-

spective articles of the pair at the adjacent sides thereof to lie at the interior when the strips are unconnected, the strips being provided at their free ends with co-engaging fastening means.

FRANK JULIUS NELSON.
